UNITED STATES PATENT OFFICE.

JOHN Q. DAY, OF RED CLIFF, COLORADO.

SNOW-PLOW.

SPECIFICATION forming part of Letters Patent No. 299,750, dated June 3, 1884.

Application filed September 24, 1883. (No model.)

To all whom it may concern:

Be it known that I, JOHN Q. DAY, of Red Cliff, county of Summit, Colorado, have invented a new and Improved Snow-Plow, of 5 which the following is a full, clear, and exact description.

My invention relates to the class of snow-plows having a wheel with an annular groove in each side, into which the snow is gathered, 10 to be carried around to the upper side and then forced out laterally by dischargers supported in the grooves; and the invention now consists of slides or gates arranged to close the grooves behind the snow in the grooves to hold 15 it thereon until carried to the upper side, said slides also being arranged to draw into the hub or central portion of the wheel to pass the dischargers; and the invention also consists of a flaring arrangement of the outside 20 rim of the wheel to facilitate the discharge of the snow by said dischargers, all as herein-after fully described.

Reference is to be had to the accompanying drawings, forming part of this specification, in 25 which similar letters of reference indicate corresponding parts in all the figures.

Figure 1 is a side elevation of the principal parts of my improved machine. Fig. 2 is a sectional elevation on the line $x-x$ of Fig. 1; 30 and Fig. 3 is a detail, mostly in plan view, showing the arrangement of the dischargers.

The large wheel or drum a , having an annular groove, b , in each side, is mounted in the strong supporting-arms c , extending forward 35 of the track-frame d , to be revolved on its shaft e by chains or other belts on the pulleys f , to gather the snow into the grooves b by the shovels g , which force it through the openings h inside of the rim i , to be carried up in the 40 wheel to the dischargers j , which throw the snow out to the sides of the track. I have found in the use of such machines that the snow is liable to slide down the insides of the rims i and clog the openings h , so as to prevent the 45 machine from working properly. I have therefore arranged the sliding gates k to slide out from the central hub or drum of the wheel just in advance of the opening h , to stop the sliding back of the snow and make sure of its being carried up, and to operate these gates so 50 that they will operate at the proper time, and

will also draw in at the top to pass under the dischargers j . I have attached them to a yoke, l , which works on eccentric cams m , attached to the frame, so that while the gates and the 55 yoke revolve around the eccentric with the wheel, the gates will be projected below and withdrawn at the top. I use the yoke instead of eccentric straps to avoid vibrating the gates, also the connecting-joints that would be necessary with that arrangement. I also propose in this case to have the rim i and the shovels g flare from the middle of the wheel outward, to make the grooves widest at the outer edge 60 to facilitate the discharge of the snow from the 65 grooves. The snow is gathered on the curved mold-board n as the machine moves along the track, and is shoveled or scraped therefrom into the wheel-grooves by the shovels g when they pass down the mold-board. The scrapers also gather up the snow to some extent in 70 front of the mold-board.

Having thus described my invention, I claim as new and desire to secure by Letters Patent—

1. The stop-gates k , in combination with a 75 wheel having annular side grooves, b , shovels g , and dischargers j , said stop-gates being arranged for and provided with means to cause them to project at the lower part of the wheel to stop the snow in the grooves and withdraw 80 at the upper part to pass the dischargers, substantially as described.

2. The stop-gates k , the yoke l , and the stationary eccentrics m , in combination with a wheel having annular side grooves, b , shovels 85 g , and dischargers j , said stop-gates being arranged to project at the lower part of the wheel to stop the snow in the grooves and to withdraw in the upper part of said wheel to pass the dischargers, substantially as described. 90

3. In a snow-wheel having annular grooves b in the sides, shovels g , for gathering the snow, and the dischargers j , for throwing out the snow, the outer rim, i , arranged to flare from the bottom of the grooves outward, to facilitate the 95 discharge of the snow, substantially as described.

JOHN Q. DAY.
